UNITED STATES PATENT OFFICE.

FRANK F. SUTER, OF WEST UNITY, OHIO.

BAG-HOLDER.

1,290,405.

Specification of Letters Patent.

Patented Jan. 7, 1919.

Application filed February 8, 1916. Serial No. 77,108.

To all whom it may concern:

Be it known that I, FRANK F. SUTER, a citizen of the United States, residing at West Unity, in the county of Williams and 5 State of Ohio, have invented certain new and useful Improvements in Bag-Holders; and I do hereby declare the following to be a full, clear, and exact description of the invention, such as will enable others skilled in 10 the art to which it appertains to make and use the same.

This invention is a bag holder adapted more particularly for use in connection with threshing machines, although it may be used 15 in various other lines of work.

The purpose of this invention is to provide simple efficient and economical means which can be readily mounted and to which may be secured a bag or other receptacle 20 while such receptacle is being filled through a discharge pipe of the chute.

Other advantages and purposes of the invention will become apparent from the following detail description, taken in connection 25 with the accompanying drawings.

While a preferred embodiment of the invention is illustrated in the accompanying drawings, it is to be understood that the structure therein disclosed is for the 30 purposes of illustration, and not as defining the limits of the invention.

In the drawings:

Figure 1 is a front elevation disclosing a bag in position on one of the terminal pipes. 35 Fig. 2 is a sectional view disclosing the means to direct the material through one of the pipes.

Fig. 3 is a rear elevation showing means to support the chute; and 40 Fig. 4 is a detail view of the material directing device.

Fig. 5 is a detail view of the clamping band for holding the bag on the terminal pipe.

Referring more particularly to the embodiment of the invention disclosed in the drawings, the chute is shown as a cylindrical member 1 which may be of any preferred length and which may be made of any suitable material. The lower end of this chute is shown provided with a plurality of terminals 2. These terminal discharge pipes are preferably flared at the mouth 3 as illustrated in Fig. 1, so that the diameter of the 50 mouth of the terminal is greater than the diameter at the neck 4 thereof.

Suitably mounted within the chute is a deflector 5, shown in the form of a curved plate which is pivotally mounted by suitable means, such as the pinions 6 engaging the 60 walls of the chute at the neck 4. One of the pinions 6 may be provided with a handle 7 whereby the deflector can be rotated within the chute to direct the material to one or the other of the pipes 2.

65

One form of bag holder is illustrated at 8 in the drawings, wherein a band is disclosed as encircling the pipe 2, the diameter of the band when in its rest position being less than the diameter of the mouth 3 of the pipe 2, 70 but of a sufficient diameter to loosely slide upon the upper portion of the pipe 2. This band 8 may be of any suitable material, such as resilient metal, and is cut at one portion thereof to provide expanding ends 9. 75 These ends are preferably connected by a yoke or arch 10, which may be of suitable material and if desired, may be of resilient material. The yoke 10 forms suitable stiffening means for the band in preventing the 80 ends 9 from expanding to too great a distance, and also serves as means to maintain the band 8 at the upper end of the pipe 2 by engaging with a hook 11 carried by the pipe 2, when it is not desired to use the band 85 for securing a bag to the pipe. If desired, a handle 12 may be secured to the band 8 to readily move the band to its various positions on the pipe.

The device may be supported in any suitable manner. One means of support is shown by a foldable tripod element, the legs of which are pivotally connected at 13. The legs 14 are shown provided at one end with reduced portions to form upper nibs 15 and 95 lower nibs 16, the lower nibs 16 serving as means to engage the supporting surface, such as the floor or ground. The upper nibs 15 are adapted to engage ears which are mounted on the chute. Three of these ears 100 are shown, one of which 17^a is secured to the body of the chute passing the juncture of the pipes 3, another ear 17^b is on one pipe and still another ear 17^c, is on the other pipe, the ears 17^b, 17^c being on one side of 105 the chute, while the ear 17^a is shown on the other side of the chute.

The ears are shown as angle plates with one member of each of the angle plates provided with an aperture through which the 110 nibs 15 may be passed to permit the respective plates 17 to rest against the shoulders 18

at the ends of the legs. It will be understood, therefore, that the legs are detachable from the chute and capable of being folded into a compact space.

5 In operation, the mouth of the bag is passed through the flared end 3 of the pipe 2, the ring 8 is then brought down over the bag and spread out at the flared mouth, to frictionally engage the bag. When the bag 10 shall have been filled, the control plate 5 can be rotated to cut off the supply of material and the ring 8 may be lifted from engagement with the bag and retained out of its engagement by hooking the yoke 10 over 15 the hook 11.

The device may be mounted in any desired manner from a threshing machine, or may be supported on a plurality of legs 11, which may be detachably secured to the 20 device.

Having thus described my invention, what I claim as new and desire to secure by Letters Patent of the United States, is:—

1. In a device of the class described, a 25 chute having a terminal pipe, a resilient encircling band positioned freely around the pipe to frictionally engage a bag and retain it in position over the mouth of the pipe, said band being provided with a yoke-shaped 30 supporting and stiffening member which is interposed as a part of the encircling band,

and a hook carried by the pipe to engage the yoke-shaped member to retain the band out of operative position with relation to the mouth of the pipe. 35

2. In a device of the class described, a chute having a discharge pipe provided with a flared terminus, and a retaining band loosely mounted on the pipe above, and adapted to have binding engagement with, 40 its flared terminus, said band being split at one portion and provided with a yoke-shaped stiffening device to connect the ends of the band, said yoke-shaped pipes being positioned at right angles to the band so 45 that the yoke will lie against the discharge pipe substantially in the plane of the band.

3. In a device of the class described, a flared discharge pipe, a resilient band loosely mounted thereon above said flared 50 portion, said band being split, and a stiffening yoke interposed between the ends, said band being designed to frictionally engage a material placed between it and the flared portion of the pipe. 55

In testimony whereof, I affix my signature, in presence of two witnesses.

FRANK F. SUTER.
